Leo Hayes,

WITNESS:

Ben Durfee
INVENTOR
BY *Victor J. Evans*
ATTORNEY

UNITED STATES PATENT OFFICE.

BEN DURFEE, OF WICHITA, KANSAS.

SIGNBOARD.

Application filed June 30, 1922. Serial No. 571,881.

To all whom it may concern:

Be it known that I, BEN DURFEE, a citizen of the United States, residing at Wichita, in the county of Sedgwick and State of 5 Kansas, have invented new and useful Improvements in Signboards, of which the following is a specification.

This invention relates to signs, particularly to that type which might be described 10 as field signs or bill boards, and has for its object the provision of a sign of novel construction and so mounted as to swing with the wind and not only thus attract more attention than a stationary sign but also relieve itself of the wind pressure so as to 15 avoid being blown down.

An important object is the provision of a sign of this character which may be supported merely by posts which do not even 20 have to be braced, even though the sign is made of large size, the simplicity of the mounting resulting from the fact that the sign will swing to accommodate itself to whatever wind pressure impinges against it.

25 An additional object is the provision of a device of this character which will be simple and inexpensive in manufacture, efficient and durable in use and a general improvement in the art.

30 With the above and other objects and advantages in view the invention consists in the details of construction to be hereinafter more fully described and claimed and illustrated in the accompanying drawings, in 35 which:

Figure 1 is a front elevation,

Figure 2 is a rear elevation, and

Figure 3 is a vertical section.

Referring more particularly to the drawings I have shown my sign as comprising a 40 rectangular frame including upper, lower and intermediate bars 10, 11 and 12 respectively connected at their ends by transverse bars 13, all of these bars being constructed 45 either of wood, angle iron or any other material which is suitable and which would naturally depend upon the size of the sign. The front of the frame is covered with any 50 suitable sheathing 14 upon which the advertising matter is painted or otherwise inscribed. I also prefer to provide an intermediate transverse cross bar 15 and diagonal brace bars 16 at the corners where the end bars 13 join the bars 10 and 11 and where 55 the cross bar 15 joins these bars 10 and 11 for the purpose of making the structure more

rigid. The sheathing 14 might be sheet metal, ordinary boards extending either lengthwise or crosswise or may be matched boards extending transversely of the frame 60 as indicated in the drawings, the sheathing being naturally painted with some weather proof coating to increase the durability. I also provide truss rods 17 which are connected with the lower end of the cross bar 15 65 and with the junctures of the uppermost intermediate bars 12 with the end bars 13, these truss rods having turn buckles 18 interposed therein for effecting tightening.

Extending longitudinally of the frame immediately below the uppermost longitudinal bar 12 is a supporting shaft 19 which might be solid but which is preferably a pipe and the ends of this member project considerably beyond the end of the end bars.

The mounting consists merely of a pair of posts 20 suitably anchored within the ground and through which the ends of the member 19 are passed, retaining elements 21 being secured against the outer sides of the posts 80 for preventing lengthwise shifting of the sign when mounted.

In the use of the sign it will be apparent that it will be very attractive and that it will attract attention owing to the fact that it will swing in the wind and consequently be more conspicuous than a purely stationary sign. In the event of a very high wind it is apparent that the sign will swing upon its shaft so as to accommodate itself to the wind 90 and to relieve the pressure impinging against it, thus avoiding being blown down.

While I have shown and described the preferred embodiment of the invention it is of course to be understood that I reserve the right to make such changes in the form, construction and arrangement of parts as will not depart from the spirit of the invention or the scope of the subjoined claims.

Having thus described my invention I 100 claim:

1. A sign of the character described comprising a rectangular frame including upper and lower and intermediate longitudinal bars connected at their ends by transverse 105 bars and connected at their centers by another transverse bar, diagonal brace bars located at the junctures of said end and intermediate cross bars with the uppermost and lowermost longitudinal bars, truss rods connected with the lower end of the intermediate cross bar and with the transverse end 110

bars and provided with turn buckles, and a shaft secured to the frame adjacent the uppermost intermediate longitudinal bar for mounting the sign structure upon supporting posts.

2. A sign of the character described comprising a rectangular frame including upper, lower and intermediate longitudinal bars connected at their ends by transverse bars 10 and at their centers by another transverse bar, diagonal braces located at the junctures of said bars, truss rods connected with the

lower end of the intermediate transverse bar and with the outer transverse bars near the upper portions thereof and equipped with 15 turn buckles, a facing secured upon and covering one side of the frame, supporting posts formed with horizontally aligned sockets and a horizontal shaft secured to the frame above the center thereof and engaging within the 20 sockets in said posts.

In testimony whereof I affix my signature.

BEN DURFEE
